WITNESS:

UNITED STATES PATENT OFFICE.

FRANK R. BOWLBY, OF COTTONWOOD FALLS, KANSAS.

RAILWAY-RAIL JOINT.

1,390,489.

Specification of Letters Patent. Patented Sept. 13, 1921.

Application filed December 13, 1920. Serial No. 430,265.

To all whom it may concern:

Be it known that I, FRANK R. BOWLBY, a citizen of the United States, residing at Cottonwood Falls, in the county of Chase 5 and State of Kansas, have invented new and useful Improvements in Railway-Rail Joints, of which the following is a specification.

My present invention has reference to improvements in means for connecting the meeting ends of railway rails.

My object is to produce a rail joint in which a chair member, on which the rails rest is provided, and an angle flange is arranged on the chair and is disposed in the fishing spaces of the rails, while wedge means are employed which engage between a flange on the chair and the angle bar to hold the latter in tight engagement with 20 the rails, and force the said rails against an integral rail engaging portion on the chair.

A further object is the production of simple means for effectively connecting the 25 meeting ends of railway rails to hold the rails against sinking, side or tilting movement, which shall be of a simple construction, and readily applied to or detached from the rails.

The foregoing, and other objects which will appear as the nature of the invention is better understood, may be accomplished 30 by a construction, combination and operative arrangement of parts, such as is disclosed by the drawings which accompany 35 and which form part of this application.

In the drawings:—

Figure 1 is a side elevation of two rails constructed in accordance with this invention.

Fig. 2 is a top plan view thereof.

Fig. 3 is a sectional view on the line 3—3 of Fig. 2.

Fig. 4 is a sectional view on the line 45 4—4 of Fig. 1.

Fig. 5 is a view of the chair member of the improvement.

Fig. 6 is a detail sectional view of the wedge members.

The confronting ends of two railway rails of the ordinary construction, are indicated, in the drawings, by the numeral 1 respectively. The supporting ties for the rails are indicated by the numeral 2.

The meeting ends of the rails 1 rest upon 55 the flat base 3 of the chair member 4 of the improvement. The chair rests on two of the ties 2, and is spiked to the said ties, as at 5.

The chair, adjacent one of its edges is 60 integrally formed with an upstanding flange 6. The inner wall of this flange is straight and the lower portion, in a line with the upper face of the base is grooved longitudinally, as at 7. The straight plate 8 of 65 the flange, upon the inner face thereof, is channeled longitudinally, as at 9 to provide air spaces, and also to provide means whereby the said plates 9 will more effectively grip the outer faces of the webs 10 of the rails 70 1. The upper wall of the groove 7 is arranged at an angle so that the base flanges 11 of the rails 1 will be snugly received therein. The flange 6 has its vertical plate 8 provided with transverse openings which 75 register with the usual elongated openings in the webs of the rails, so that securing means, in the nature of the usual bolts 12, may pass through these openings. The bolts are, of course, engaged by nuts 13 and 80 locking means may be provided for the nuts.

The flat face of the base 3, at suitable intervals, is provided with openings 14 through which water or other moisture may 85 drain.

The rails, on the faces thereof opposite those engaged by the flange on the chair, have arranged in their fishing spaces an angle bar 15. Their securing means, heretofore referred to, also pass through openings in the vertical plate of the angle bar. The horizontal plate or flange of the angle bar contacts with the edges of the base 90 flanges of the rails.

On the flat base 3, outward of the angle bar 15, there is integrally formed an upstanding longitudinally extending lug or flange 16. The inner face of the lug is beveled inwardly, as at 17. The horizontal 95 flange 18 of the angle bar 15 is of a height approximately equaling that of the lug 17, and has its outer face inclined inwardly from the center to the ends thereof, as indicated by the numeral 19. Between the beveled walls 19 and the inwardly inclined wall 17 of the lug 16 there are arranged 100 wedge blocks 20 respectively. These wedge 105

blocks enter the passages between the lug and the angle bar, from the opposite ends of the chair. The inner faces of the wedge blocks are straight, but are arranged at an angle from their inner to their outer ends, and these angle surfaces 21 are designed to contact with the angle surfaces on the outer face of the horizontal flange of the angle bar. The opposite or outer faces of the 10 wedge blocks are beveled, as at 22, and these beveled walls are designed to be received against the beveled wall on the inner face of the lug 17.

Each of the wedge blocks 20 has a central opening passing therethrough. The opening 23 in one of the blocks is non-threaded, but the opening 24 in the other block is threaded. Passing through the non-threaded opening 23 and engaging with the threads 20 in the opening 24 of the second wedge block is a bolt member 25. The bolt member has its head preferably kerfed, as at 26 whereby a suitable instrument, such as a screw driver, may have its bit inserted in 25 the said kerf and the driver turned until the wedge members are forced toward each other. The longitudinal movement of the wedge members toward each other will cause a pressure to be exerted upon the 30 angle bar, forcing the angle bar tightly into the fishing spaces of the rails, and consequently forcing the rails against the inner face of the flange 6 on the chair 4. Suitable locking means, such as is illustrated 35 by the numeral 27 may be provided for holding the bolt against turning, and it is thought that the foregoing description, when taken in connection with the drawings will fully set forth the construction and 40 advantages of the improvement without further detailed description. It is thought necessary to state, however, that the showing and description refer to a satisfactory embodiment of the improvement as it now appears to me, and that I may, at a later date, 45 make such changes therefrom as fall within the scope of what is claimed.

Having described the invention, I claim:—

1. In a means for connecting the meeting 50 ends of two railway rails, a chair on which the rails rest, a flange on said chair having its inner surfaces received in the fishing spaces of the rails and also receiving the base flanges of the rails, an angle bar engaging the opposite sides of the rails, an upstanding longitudinal lug on the base of the chair spaced from the angle bar, wedge means between the angle bar and lug, adjusting means for said wedge means, and 55 locking means for said adjusting means.

2. In a means for securing the meeting 60 ends of railway rails, a chair upon which the rail ends rest, said chair having an integral flange whose inner face is shaped to 65 be received in the fishing spaces of the rails

and to receive the base flange of the rails therein, an angle bar received in the fishing spaces on the opposite sides of the rails and contacting with the base of the rail flanges, securing means through the angle bar rails and flange of the chair, said angle bar having its horizontal flange, on its outer surface inclined inwardly from the center to the ends thereof, a lug integrally formed on the base of the chair outward of the angle bar 70 and having an inner inclined wall, wedge members having their opposite sides complementary with the outer walls of the angle bar and the inner wall of the lug, received between said walls, means on one of the 75 wedge blocks engaging with the other wedge block for moving the blocks toward or away from each other, and means for locking said adjusting means.

3. In a means for securing the meeting 80 ends of two railway rails, a chair, including a flat base on which the rails rest, a flange integrally formed on the chair adjacent to one edge thereof, and having its inner face shaped to be received in the fishing spaces 85 of the rails, to underlie the heads of the rails and to receive the base flanges of the rails, the inner straight face of the flange having longitudinal channels therein, the base of the chair having spaced openings 90 therein, an angle bar received in the opposite fishing spaces of the rails and resting on the chair, said angle bar having its horizontal flange, on its outer surface straight, and beveled from the center to the ends 95 thereof, an upstanding lug integrally formed on the base of the chair outward of the angle bar and having its inner face beveled from its top inwardly to its bottom, opposed 100 wedge members having their opposite faces shaped complementary with the beveled surfaces of the angle bar and the inclined surface of the lug, received between such surfaces, said wedge blocks having central openings therethrough, one of which being threaded, a bolt member passing through the non-threaded opening and engaging in the threaded opening, means for locking the 105 bolt when the wedge blocks are adjusted.

4. In a means for securing the meeting 110 ends of two railway rails, a chair, including a flat base on which the rails rest, a flange integrally formed on the chair adjacent to one edge thereof, and having its inner face shaped to grip the webs of the rails and to receive the base flanges of the rails, the opposite edge of said base having an upstanding lug integrally formed and extending longitudinally thereon, said lug having its inner face beveled from its top inwardly to 115 its bottom, of an angle bar engaging the opposite side of the webs of the rails and resting on the base of said chair, said angle bar having a horizontal flange, the outer surface thereof being straight, said flange 120

being beveled from the center to its ends, opposed wedge members having their opposite faces shaped complementary with the beveled surfaces of the angle bar and the inclined surface of the lug, received between such surfaces, said wedge blocks having central openings therethrough, one of which be-

ing threaded, a bolt member passing through the non-threaded opening and engaging in the threaded opening, and means for locking 10 the bolt when the wedge blocks are adjusted.

In testimony whereof I affix my signature.

FRANK R. BOWLBY.
